INTERFITTING KNIFE AND FORK SET

John M. Williams, 1133 W. Roeser Road, Phoenix, Ariz.

Filed Oct. 2, 1961, Ser. No. 66,918

Term of patent 14 years

(Cl. D22—3)

FIG. 1 is a side elevational view of an interfitting knife and fork set;

FIG. 2 is an edge view thereof, as seen from the right of FIG. 1;

FIG. 3 is a top view thereof;

FIG. 4 is a bottom view thereof;

FIG. 5 is another view of FIG. 1 showing the fork unit removed therefrom;

FIG. 6 is another view of FIG. 1 showing the knife unit removed therefrom;

FIG. 7 is an end view of the detached knife unit shown in FIG. 5;

FIG. 8 is an end view of the detached fork unit shown in FIG. 6.

I claim:

The ornamental design for an interfitting knife and fork set, as shown.
